UNITED STATES PATENT OFFICE.

ETHAN I. DODDS, OF PULLMAN, ILLINOIS, ASSIGNOR TO THE PULLMAN COMPANY,
OF CHICAGO, ILLINOIS, A CORPORATION OF ILLINOIS.

METAL ORE-CAR.

No. 874,576.

Specification of Letters Patent.

Patented Dec. 24, 1907.

Application filed June 24, 1905. Serial No. 266,811.

To all whom it may concern:

Be it known that I, ETHAN I. DODDS, a citizen of the United States, residing at Pullman, in the county of Cook and State of Illinois, have invented certain new and useful improvements in Metal Ore-Cars, of which the following is a specification.

This invention relates to metal cars such as are employed in transporting ore, coke, and other more or less sticky and adhesive classes of lading; and the general object of the invention is to provide a car of such a form and construction that it will readily effect a full and complete discharge of its load by gravity without allowing portions of the load to adhere to its walls, necessitating a manual discharge of such residue.

Another object of the invention is to provide a car combining a maximum of strength, rigidity and durability with light weight and facility of easy repair.

To these ends my invention consists in a metal car having the peculiarities of form and structure substantially as hereinafter described and more particularly pointed out in the claims.

A car constructed in accordance with my invention is illustrated in the accompanying drawings, wherein,—

Figure 1 is a part plan and a part horizontal sectional view; Fig. 2 is a part side elevation and a part vertical sectional view; Fig. 3 is a vertical cross-sectional view on the line 3—3 of Fig. 1, on an enlarged scale; Fig. 4 is a similar transverse sectional view on the line 4—4 of Fig. 1; Fig. 5 is an end elevational view; and Fig. 6 is a fragmentary horizontal sectional view through a portion of the center and one side of the car.

Referring to the drawings, 10 designates the central longitudinal sills of the car formed of inwardly facing channel beams, the ends of which extend through and a slight distance beyond the body-bolsters, hereinafter described. 11 are the side sills also formed of outwardly facing channel beams connected at their ends by end sills 12. The body portion of the car which, as shown more particularly in Fig. 2, lies inwardly of and between the body-bolsters of the under frame, is formed essentially of side-plates 13 and end-plates 14 suitably united and reinforced as hereinafter described. The side-plates 13 are perpendicular from the bottom of the car 55 to the horizontal plane of the tops of the side

sills 11, and from the latter plane the plates have a slight inward taper, as shown more particularly in Fig. 4. The end-plates 14 are also cut at their outer edges on a taper to conform to the taper of the sides of the car. 60 The end plates flare outwardly and upwardly as shown in Fig. 2, and are united at their inner or meeting edges by a channel 15 disposed with its flanges protruding outwardly of the car-body. The top of the car-body on 65 all four sides is reinforced and stiffened by angles 16, and the plates 13 and 14 are united at the vertical corners by channels 17 having their webs bent into rectangular form, as clearly shown in Fig. 6. The side-plates 13 70 are securely riveted to side stakes 18, which latter are preferably made from sections of I-beam having its web cut on the bias so as to leave a short section of the outer flange 18^a between the upper and lower oblique edges 75 for riveting to the side sills 11 (Fig. 4). The ends of the car-body are rigidly secured against longitudinal shifting by means of diagonal braces 19 herein shown as formed by outwardly facing channel beams connected 80 at their upper ends to the central inclined channel 15 of the end walls and at their lower ends to the center sills 10.

Bent plates 20 disposed longitudinally of the car-body overlying the sides of the center 85 sills and with upwardly convergent upper portions (Fig. 4) constitute central load-deflectors as well as reinforcing members for the longitudinal sills, said plates having end flanges 20^a; whereby they are riveted to the end plates 14. The bottom of the car-body is constituted by a plurality of transversely hinged and operating doors 21, each door comprising a pair of plates lying on opposite sides of the car-body, respectively, and united 95 by means of an I-beam 22 having its ends cut on the bias, said beam acting both as a connector and equalizing bar for the door sections. These doors are hinged at 23 (Fig. 2) in inversely disposed pairs or twins, and may 100 be operated by a windlass 24 through the medium of chains 25 and idler pulleys 26. However my present improvements are not concerned with any particular door-operating mechanism, and any other suitable mechanism may be substituted for that herein shown.

The body-bolsters which lie outside of and beyond the ends of the car-body are disposed transversely between the side sills 11 and the 11

center sills 10, and are of hollow or box-like form, each comprising a pair of outwardly facing pressed beams 27 formed with top, bottom and outer end flanges. Said beams are united 5 and reinforced in their upper edges by a tension plate 28, and on their lower edges by a compression plate 29. The outer end flanges of the beams 27 are riveted to the side sills 11 (Fig. 3), while the inner ends of said beams 10 are united to the center sills by angles 30. It will be observed that the car herein shown and described is of greater width at the bottom than at the top, while its end walls slope downwardly and inwardly in the 15 usual manner. By this construction the compression or congestion of the load as it discharges, due to the downward convergence of the end walls, is largely offset and neutralized by the downward divergence of 20 the side walls which affords perfect freedom for the action of gravitation and greatly facilitates the freedom of discharge and prevents the tendency of the load to adhere to the side and end walls of the car. 25 This patent is intended to embrace only so much of the disclosure made herein as is covered by the claims.

I claim:

1. In a car of the class described, the combination with the side sills, of a series of side stakes secured to the inner faces of said side sills, and a load-holding receptacle having its side walls secured to said side stakes, substantially as described. 30
2. In a car of the class described, the combination with the side sills, of a series of side stakes secured to the inner faces of said side sills and extending below the latter, and a load - holding receptacle having the full 40 depth of said side stakes and secured through its side walls to the latter, substantially as described. 35
3. In a car of the class described, the combination of side sills, side stakes disposed inside of and secured to said side sills, and a car body whose sides are attached to said side stakes, substantially as described. 45
4. In a car of the class described, the combination of side sills, side stakes having inner 50 and outer flanges, said outer flanges being secured to the inner surfaces of said side

sills, and a car body fastened to the inner flanges of said side stakes, substantially as described.

5. In a car of the class described, the combination of channel side sills disposed with their flanges extended outwardly, side stakes having short outer flanges and long inner flanges, the webs of said stakes tapering from the ends of said short outer flanges to 60 said inner flanges, said outer flanges being fastened to the inner surfaces of said channel side sills, and a car body secured to the inner flanges of said side stakes, substantially as described. 65

6. In a car of the class described, the combination of side sills, side stakes disposed inside of and secured to said side sills, and a car body having downwardly divergent side walls and downwardly convergent end walls 70 attached to said side stakes, substantially as described. 70

7. In a car of the class described, the combination with the under-frame, of a load-holding receptacle mounted centrally on said 75 under-frame, and inclined end braces connecting the upper ends of said receptacle with the center sills of the under-frame inside of the body-bolsters, substantially as described. 80

8. A railway car stake having flanges of unequal length on opposite edges of a web which tapers from one end of the shorter flange toward the longer flange, substantially as described. 85

9. A railway car stake having flanges of unequal length on the opposite edges of a connecting web which tapers from both ends of the shorter flange to the longer flange, substantially as described. 90

10. A railway car stake I-shaped in cross-section, the oppositely disposed flanges on one edge of the web being shorter than the oppositely disposed flanges on the other edge of the web, said web tapering from the ends 95 of the shorter flanges toward the longer flanges. 95

ETHIAN I. DODDS.
